US0D1096143S

(12) United States Design Patent (10) Patent No.: US D1,096,143 S
(45) Date of Patent: * Oct. 7, 2025

(54) TOTE BAG

(71) Applicant: CASE-MATE, INC., Atlanta, GA (US)

(72) Inventors: Amber James, Brookhaven, GA (US);
Andrew Harper, Lilburn, GA (US)

(73) Assignee: CASE-MATE, INC., Atlanta, GA (US)

() Term: 15 Years

(21) Appl. No.: 29/995,893

(22) Filed: Mar. 28, 2025

Related U.S. Application Data

(62) Division of application No. 29/951,091, filed on Jul. 8, 2024.
